AUTOMATIC MATERIAL HOLDBACK MEANS
FOR SEWING MACHINES

Meyer Unger, Oneonta, N. Y.

Application July 23, 1940, Serial No. 347,047

12 Claims. (Cl. 112—239)

This invention relates to automatic material hold-back means for sewing machines and is of the general type disclosed in the application for patent filed by Meyer Unger on March 15, 1940, Serial No. 324,181, and provides as an improvement thereover a simplified construction for accomplishing the objects ascribed to the invention disclosed in said application.

A further object of the present invention is to provide an attachment for a sewing machine of any type, the hold-back foot being operative for arresting movement of the material after the same passes the usual presser foot and including a worm on the shaft beneath the bed plate of the sewing machine that has the shuttle associated therewith, with the worm driving a worm wheel that in turn operates devices associated with the hold-back foot for rendering said devices operative at predetermined intervals when a predetermined number of stitches have been taken to effect raising of the hold-back foot so that the sewed material will be free of all stretching action normally inherently produced by the tendency of the operator to pull the material by hand rearwardly of a presser foot.

The invention further includes manually operable means for raising the hold-back foot at will and a knee-operated or other lever to effect simultaneous raising of the pressure foot and hold-back foot for the release of material when desired.

With the above and other objects of the invention that will become apparent as the nature thereof is better understood, the same consists in general of certain novel details of construction and combination of parts hereinafter more fully described, illustrated in the accompanying drawings and claimed.

In the drawings:

Figure 1 is a side elevational view, partly broken away, of a sewing machine equipped with an automatically operating material hold-back foot and the devices associated therewith.

Figure 2 is an outer end elevational view of the head of the sewing machine, showing the tensioned hold-back foot disposed rearwardly of the presser foot.

Figure 3 is a fragmentary side elevational view, partly in section, of the head end of the sewing machine with the hand-operated lever for raising the hold-back foot illustrated in dotted lines together with the hold-back foot in raised positions.

Figure 4 is a horizontal sectional view taken on line 4—4 of Figure 3,

Figure 5 is a fragmentary bottom plan view showing a worm on the shuttle shaft engaged with the worm wheel that operates the devices for periodically raising the hold-back foot.

5 Figure 6 is a fragmentary end elevational view showing the driving belt guide.

Figure 7 is a detail sectional view taken on line 7—7 of Figure 5, showing a lug facially projecting from the worm wheel for engagement with a cam on an operating arm of the mechanism for raising the hold-back foot, and

10 Figure 8 is a detail sectional view taken on line 8—8 of Figure 5.

The hold-back foot attachment is associated with a sewing machine of standard construction that includes a bed plate 15 that has a hollow upright 16 rising from one end thereof, the upper end of the upright carrying a lateral horizontally extending overhanging hollow arm 17 that carries at its free end above the bed plate 15 a vertical hollow head 18. A horizontal drive shaft 19 extends through the upper end of the upright 16 and the overhanging arm 17, the end of the horizontal shaft 19 projecting outwardly of the upper end of the hollow upright 16 carrying a fly wheel 20 and a belt drive sheave 21. The other end of the shaft 19 has a conventional driving connection with the bar 22 vertically reciprocable in the hollow head 18, the bar 22 carrying at its 20 end the usual sewing machine needle 23. A downwardly tensioned vertically sliding bar 24 is mounted in the head 18 and carries at its lower end an ordinary presser foot 25 that engages the throat plate 26 of the bed plate 15, the downwardly tensioned bar 24 carrying the usual abutment to be engaged by the cam lever 27 to effect manual raising of the presser foot 25.

The automatically operating material hold-back foot attachment for the sewing machine includes a mounting plate 28 overlying a side of the hollow head 18 with an angle arm 29 carried thereby with an opening therein for the passage of the threaded bolt 30 upon which the cam lever 27 for raising the presser foot is pivoted, the 40 nut 31 threaded upon the bolt 30 retaining the mounting plate in position while the two screws 32 threaded through the mounting plate 28 are engaged with the hollow head 18 to effect a substantial support for the mounting plate. The plate 28 is provided with a slotted opening 33 for the passage of the cam lever 27. A tubular guide 34 is carried by one edge of the mounting plate 28 in the vertical plane with and rearwardly of the 45 downwardly tensioned rod 24 as illustrated. A rod 35 is vertically slidable in the tubular

guide 34 and is of a length to project at all times above and below said guide, the lower projecting end of the rod 35 in proximity of the lower end of the tubular guide being threaded as at 36 for a portion of its length for the reception of an adjustable nut 37 while a coil spring 38 surrounds the rod 35 between said nut 37 and the lower end of the tubular guide for normally tensioning the rod 35 in a downward direction. A holdback foot 39 is adjustably mounted upon the lower end of the rod 35 and is positioned post-jacent the presser foot 25 as shown in Figure 2.

The operating means for the rod 35 carrying the hold-back foot 39 includes a lever pivoted intermediate its ends on the horizontal pin 40 projecting laterally of the overhanging arm 17, the opposite lever arms 41 and 42 of the lever extending longitudinally of the overhanging arm 17 with the end 42 having a pivotal connection 43 with the upper end of the rod 35. The free end of the lever arm 41 is adjustably attached to the upper end of a vertical rod 44 by means of the nut 45 threaded on the upper end of said rod 44 and engaged with the upper side of the lever arm 41, the lower end of said rod 44 as shown in Figures 1 and 5 extending downwardly through an opening 46 in the bed plate 15 with a hook 47 upon its lower terminal end engaged in an opening in the flattened end 48 of a lever 49 that is pivotally mounted beneath the bed plate 15 at the other end thereof as shown at 50 upon a pin 51 depending from the bed plate. It will be understood that the rod 35 is downwardly tensioned by the spring 38 which normally moves the free end of the lever arm 42 in a downward direction and the free end of the lever arm 41 in an upward direction so that the free end of the lever 49 is normally at its limit of upward movement on its pivot bearing 50.

The material hold-back foot 39 may be raised at will by means of manually operated devices shown more clearly in Figures 1 and 3 as comprising a disk cam 52 eccentrically mounted as at 53 upon the upper end of the mounting plate 28 and carrying a manipulating handle 54, the cam and handle being shown in their shifted dotted line positions in Figure 3 with the cam 52 engaged with the underside of the free end of the lever arm 42 for raising the same and carrying therewith against the tension of the spring 38, the rod 35 and material hold-back foot 39 at the lower end of said rod. The handle 54 is limited in its downward movement to an inoperative position by moving into engagement with the upper screw 32 that aids in securing the mounting plate 28 in position.

It is intended that the sewing machine needle 23 produce a predetermined number of stitches while the material hold-back foot 39 is in its lower operative position and to accomplish this object devices are provided to effect periodic pivotal movements of the lever 49 on its pivot bearing 50, these devices including the longitudinally extending drive shaft 55 below the bed plate 15 that has a belt connection 56 extending upwardly through the hollow upright 16 to a pulley 57 upon the drive shaft 19, the belt being twisted as shown in Figure 1 and carrying parallel rows of spaced outwardly projecting pins 58 while a guide frame 59 carried by the lower side of the bed plate 15 as shown in Figures 5 and 6 has an arcuate edge 60 slightly spaced from said belt between said rows of pins to assure proper tracking of the belt 56 on the shaft 55. The shaft 55 at its opposite end has the sewing ma-

chine shuttle associated therewith. A worm 61 is fixed to the shaft 55 intermediate the ends thereof.

5 A worm wheel 62 is journaled upon a pin 63 depending from the lower face of the bed plate 15 and is engaged with the worm 61, the worm wheel 62 at a point between the pivot 63 and peripheral edge thereof overlying the lever 49 in proximity of the lower pivot pin 51. An abutment lug 64 depends from the worm wheel 62 inwardly of the peripheral edge thereof and is adapted during rotation of the worm wheel to move into engagement with a cam 65 rising from the lever 49 for moving the lever on its pivot bearing 51 and exerting a downward pull on the rod 44 to operate the lever arms 41 and 42 to raise the rod 35 carrying the material hold-back foot 39. When the abutment lug 64 is carried beyond the cam 65, the downwardly tensioned rod 35 raises the free end of the lever 49 and effects lowering movement of the material hold-back foot 39 into its material hold-back position.

Should it be desired to simultaneously raise the presser foot 25 and the material hold-back foot 39 by a single operation, there are provided devices including a lever having lever arms 66 and 67 pivoted intermediate their ends upon the lever pivot 49 as shown in Figure 1. The free end of the lever arm 67 as shown in Figure 2 carries a pin extension 68 that projects into a laterally offset portion of the hollow head 18 that works in a slot 69 in an arm 70 carried by and movable with the sliding bar 24 that carries the presser foot 25, the pin extension 68 being normally positioned at the upper end of the slot 69 so as not to interfere with the normal operation of the sliding bar 24 by the cam lever 27. The free end of the lever arm 66 is pivotally attached as at 71 to a head 72 that carries a depending rod 73 that is attached at its lower end as at 74 to one end of a knee-operated lever 75 that is pivoted intermediate its ends as at 76 upon a bracket arm 77 depending from the bed plate 15, the connection 74 between the lower end of the rod 73 and the knee-operated lever 75 being superjacent the end 48 of the lever 49 so that when the lever 75 is operated the pin extension 68 upon the lever arm 67 raises the sliding bar 24 carrying the presser foot 25 by its engagement in a slot in the arm 70 while the end of the lever 75 to which the rod 73 is attached presses downwardly upon the end 48 of the lever 49 for raising the lever arm 42 and rod 35 carrying the material hold-back foot 39.

55 From the above detailed description of the invention it is believed that the construction and operation thereof will at once be apparent, it being noted that the material fed rearwardly under the presser foot 25 is held back by the downwardly tensioned material hold-back foot 39 until the hold-back foot is raised by rotation of the worm wheel 62 that carries the abutment lug 64 into engagement with the cam 65 on the lever 49, the stitched material being then automatically extended beyond the hold-back foot with the latter promptly lowering to its material hold-back position when the abutment lug 64 is moved beyond the cam 65 during continuous rotation of the worm wheel 62. Those materials ordinarily subjected to stretching activities by an operator who uses her hand for the drawing of the material rearwardly of the presser foot are not subjected to any stretching activities and it is possible to sew materials on the bias and materials

of any weight without any stretching action on the materials.

While there is herein shown and described the preferred embodiment of the invention, it is to be understood that minor changes may be made in the details of construction, such as will fall within the scope of the invention as claimed, it being further noted that the material hold-back foot is spaced rearwardly of the usual material feed dog associated with the presser foot and engages a smooth part of the throat plate of the sewing machine.

I claim:

1. Automatic material hold-back means for sewing machines, wherein the sewing machine includes a bed plate, a presser foot, a material feed-dog, operating means for the dog and a rotatable shaft beneath the bed plate, an automatically operated material hold-back foot post-jacent the presser foot and normally positioned to hold back material passed rearwardly of the presser foot, a downwardly tensioned rod carrying the hold-back foot and gear drive connections between the shaft and rod operative at intervals to raise the rod and material hold-back foot to release the held-back material.

2. Automatic material hold-back means for sewing machines as set forth in claim 1, wherein independently operating means are provided for separately raising the presser foot and the material hold-back foot.

3. Automatic material hold-back means for sewing machines as set forth in claim 1, wherein independently operating means are provided for separately raising the presser foot and the material hold-back foot and manually operated means for simultaneously raising the presser foot and material hold-back foot.

4. Automatic material hold-back means for sewing machines, wherein the sewing machine includes a bed plate, a presser foot, a material feed-dog, operating means for the dog and a rotatable shaft beneath the bed plate, an automatically operated material hold-back foot post-jacent the presser foot and normally positioned to hold back material passed rearwardly of the presser foot, a downwardly tensioned rod carrying the hold-back foot and gear drive connections between the shaft and rod operative at intervals to raise the rod and material hold-back foot to release the held-back material, the gear drive connections including a worm on said shaft, a worm wheel driven by said worm, a series of levers and links with an end lever of the series operatively engaged with the rod carrying the hold-back foot and with the other end lever of the series being adjacent said worm wheel and cooperating means carried by said worm wheel and said last named lever of said series adapted periodically to operate the links and levers for raising the rod and material hold-back foot.

5. Automatic material hold-back means for sewing machines as set forth in claim 1, wherein independently operating means are provided for separately raising the presser foot and the material hold-back foot, the gear drive connections including a worm on said shaft, a worm wheel driven by said worm, a series of levers and links with an end lever of the series operatively engaged with the rod carrying the hold-back foot and with the other end lever of the series being adjacent said worm wheel and cooperating means carried by said worm wheel and said last named lever of said series adapted periodically to operate

the links and levers for raising the rod and material hold-back foot.

6. Automatic material hold-back means for sewing machines as set forth in claim 1, wherein

5 independently operating means are provided for separately raising the presser foot and the material hold-back foot and manually operated means for simultaneously raising the presser foot and material hold-back foot, the gear drive connections including a worm on said shaft, a worm wheel driven by said worm, a series of levers and links with an end lever of the series operatively engaged with the rod carrying the hold-back foot and with the other end lever of the series being adjacent said worm wheel and cooperating means carried by said worm wheel and said last named lever of said series adapted periodically to operate the links and levers for raising the rod and material hold-back foot.

10 7. Automatic material hold-back means for sewing machines as set forth in claim 1, wherein independently operating means are provided for separately raising the presser foot and the material hold-back foot, the presser foot raising

15 means including a vertically slidable bar carrying the presser foot, and a cam lever engageable with said bar for raising the same, and the material hold-back foot raising means including a lever pivoted on the sewing machine with one end thereof connected to the upper end of the downwardly tensioned rod and a hand operated cam lever pivoted on the machine adapted to move the lever on its pivot to raise the material hold-back foot.

20 8. Automatic material hold-back means for sewing machines as set forth in claim 1, wherein independently operating means are provided for separately raising the presser foot and the material hold-back foot, the presser foot raising

25 means including a vertically slidable bar carrying the presser foot, and a cam lever engageable with said bar for raising the same, and the material hold-back foot raising means including a lever pivoted on the sewing machine with one

30 end thereof connected to the upper end of the downwardly tensioned rod and a hand operated cam lever pivoted on the machine adapted to move the lever on its pivot to raise the material hold-back foot, and manually operated means

35 for simultaneously raising the presser foot and material hold-back foot, including a lever pivoted on the machine, a pin and slot connection between one end of the lever and the support for the presser foot, a link rod depending from the

40 other end of the lever extending downwardly through the bed plate of the machine, a knee-operated lever pivoted on the bottom of the bed plate and to one end of which the depending link rod is attached, a second depending link rod carried by the other end of the lever attached to the rod carrying the material hold-back foot, a worm wheel-operated lever beneath the bed plate for operation of said second-named link rod and said worm wheel-operated lever being

45 arranged in the operative path of movement of the knee-operated lever for operation by the latter.

50 9. Automatic material hold-back means for sewing machines as set forth in claim 1, wherein the gear drive connections include a worm on said shaft, a worm wheel driven by said worm, a series of links and levers with the worm wheel overlying a lever of said series, an abutment lug facially depending from said worm wheel and an abutment cam on the lever underlying said worm

wheel adapted to be engaged by said abutment lug during rotation of the worm wheel for operating the series of links and levers for the raising of the material hold-back foot.

10. Automatic material hold-back means for sewing machines as set forth in claim 1, wherein the gear drive connections include a worm on said shaft, a worm wheel driven by said worm, a series of links and levers with the worm wheel overlying a lever of said series, an abutment lug facially depending from said worm wheel and an abutment cam on the lever underlying said worm wheel adapted to be engaged by said abutment lug during rotation of the worm wheel for operating the series of links and levers for the raising of the material hold-back foot, a loose connection in said series of links and levers and a manually-operated cam adapted to shift a lever of said series connected with said rod for raising the material hold-back foot at will.

11. Automatic material hold-back means for sewing machines as set forth in claim 1, wherein the gear drive connections include a worm on said shaft, a worm wheel driven by said worm, a series of links and levers with the worm wheel overlying a lever of said series, an abutment lug facially depending from said worm wheel and an abutment cam on the lever underlying said worm wheel adapted to be engaged by said abutment lug during rotation of the worm 30

wheel for operating the series of links and levers for the raising of the material hold-back foot and manually-operated means for simultaneously raising the presser foot and material hold-back

5 foot including a knee-operated lever operatively engaged with the presser foot and adapted for operation of the worm wheel-operated lever.

12. Automatic material hold-back means for sewing machines as set forth in claim 1, wherein the gear drive connections include a worm on said shaft, a worm wheel driven by said worm, a series of links and levers with the worm wheel overlying a lever of said series, an abutment lug facially depending from said worm wheel and an abutment cam on the lever underlying said worm wheel adapted to be engaged by said abutment lug during rotation of the worm wheel for operating the series of links and levers for the raising of the material hold-back foot, a loose connection in said series of links and levers and a manually-operated cam adapted to shift a lever of said series connected with said rod for raising the material hold-back foot at will, and manually-operated means for simultaneously raising the presser foot and material hold-back foot including a knee-operated lever operatively engaged with the presser foot and adapted for operation of the worm wheel-operated lever.

MEYER UNGER.
